UNITED STATES PATENT OFFICE.

WILLIAM BARNETT, OF MANSFIELD, ASSIGNOR TO THE GARFIELD INJECTOR COMPANY, OF WADSWORTH, OHIO.

STEAM-INJECTOR.

SPECIFICATION forming part of Letters Patent No. 417,463, dated December 17, 1889.

Application filed July 15, 1889. Serial No. 317,617. (Model.)

To all whom it may concern:

Be it known that I, WILLIAM BARNETT, a citizen of the United States of America, residing at Mansfield, in the county of Richland and

5 State of Ohio, have invented certain new and useful Improvements in Steam-Injectors, of which the following is a specification, reference being had therein to the accompanying drawings.

10 This invention pertains to certain new and useful improvements in steam-injectors, having for its object the provision of an injector capable of being used as a combined lifting and forcing injector, or as a forcing-injector alone, 15 or as an ejector without the forcing features; and the invention embraces an overflow-valve having its seat against an opening in the lower portion of the casing and an auxiliary overflow-valve located over the opening between 20 the water and overflow chambers, the stems of said valves being extended above and beyond the injector-casing.

The invention also comprises the details of construction, combination, and arrangement 25 of parts, substantially as hereinafter fully set forth, and particularly pointed out in the claims.

In the accompanying drawings, Figure 1 is a side elevation of my improved injector. 30 Fig. 2 is a vertical longitudinal sectional view thereof. Fig. 3 is a sectional detail.

Referring to the drawings, A designates the tubular casting or casing, having the steam-inlet arm a, the overflow-arm a', and the delivery-arm a².

B is the lower water-inlet arm or extension opening at one end into the water-chamber b of casing A.

C C' are respectively the forcing and lifting steam jets or tubes secured between the continuous steam-inlet chamber and the upper and lower water-chambers. Over the end 45 of the forcing steam-jet C is designed to fit the upper steam-valve D, the stem of which

works in a hollow threaded plug d, screwed in the end of the casing, while in the end of arm B, over jet C', is screwed a plug D', as shown in Fig. 1, or in lieu thereof a second valve D², the latter being employed when the device is

50 to be used as an ejector.

In using my invention as a combined lifting

and forcing injector only one steam-valve is absolutely necessary, the plug D' closing the outer end of the water-inlet arm. When the invention is to be used solely as a forcing-injector, the water being supplied from an elevated point, I insert a washer D³ (see Fig. 3) between the end of plug D' and the steam-jet C'. This plug and washer and the upper valve D can be interchanged when an ejector 60 is the form of device desired.

E is the lifting-tube, screwed into a flanged wall e of the water-inlet arm B, the forward end thereof being near the lower steam-jet C'.

F is the combining-tube, made or formed 65 integral with the delivery-tube f. These tubes are screwed into the flanged end f' of an inner tubular extension f² of the overflow-chamber G, and the forward end of said combining-tube is adjacent the upper steam-jet C. A 70 primary or secondary overflow-valve H, having its stem h engaging and projecting through a plug h', is seated over an opening h² in the tubular extension f².

I is the main overflow-valve, seated over an 75 opening in the lower portion of casing A. Its stem i is projected vertically through the casing and an upper plug i', whereby it, as well as the stem of the secondary valve, can be readily manipulated.

In practice, in using my device as a combined lifting and forcing injector, steam is admitted, and, the valve D being opened, the lifting of water is effected into the water-inlet arm, from which it will pass to the main 85 water-chamber b, and at the mouth of the combining-tube the water is taken up by the steam passing through jet C and forced through the tubes to the boiler or receptacle.

In the starting of the injector prior to the 90 establishment of the jet or column it is necessary to first open the overflow-valves H I, the former permitting the passage of the overflow from the water-chamber to the main overflow-chamber, from which it passes to the outer 95 atmosphere. After the column is established these valves are closed.

To use this device as a forcing-injector alone, the lower valve D² is closed, or plug D' and washer D³ are inserted in place, and the 100 water, being fed under pressure, will pass into the water-chamber and from there be carried

to the boiler by the forcing-jet of steam, as before described. Again, when the device is to be used solely as an ejector, the upper valve D is closed, or it may be replaced by a plug 5 and washer, and the steam permitted to pass through the lower series of tubes, forcing the water to the boiler or other receptacle.

The advantages of my invention will be apparent to those skilled in the art to which 10 it appertains. By means thereof I am enabled to lift hotter water than has heretofore been possible with this class of inventions, and the same can also be used as a combined lifting and forcing injector, a forcing-injector 15 alone, or as an ejector. There is also decided advantage in having the overflow-valve seated against the bottom of the casing and in projecting the valve-stems above said casing.

When the invention is to be used only as a 20 forcing-injector and as an ejector, one steam-valve is sufficient, because the valve D and plug D' and its washer can be interchanged when the ejector is the machine desired.

I claim as my invention—

25 1. A steam-injector having upper and lower series of tubes, an upper valve having a removable plug, and a lower removable plug interchangeable with said former plug and valve, substantially as set forth, whereby the 30 injector may be used for lifting and forcing, for forcing alone, or as an ejector, as stated.

2. As an improvement in steam-injectors,

the casing having the lower water-inlet arm opening thereinto and provided with steam and water lifting tubes and the valve or plug 35 fitted thereover, in combination with the upper series of tubes and the upper steam-valve, substantially as set forth.

3. A steam-injector having a lower water-inlet arm and a series of steam and water inlet 40 tubes, and the lower plug and the washer secured thereby over said steam-tube, in combination with the upper series of steam and water forcing tubes and the upper steam-valve, 45 substantially as set forth, whereby a forcing-injector is secured, as stated.

4. In a steam-injector, the combination, with the casing having the lower overflow-opening and the inner tubular extension f^2 , provided with an upper overflow-opening, of the overflow-valves seated over said openings and having stems projecting therefrom up through 50 said casing, substantially as set forth.

5. In an injector having interchangeable parts, the plug herein described and the 55 washer designed to be secured thereby, substantially as set forth.

In testimony whereof I affix my signature in presence of two witnesses.

WILLIAM BARNETT.
